CHAIN SAW HOUSING

Joseph H. Budd, Ashland, and Wallace L. Smith, Southboro, Mass., assignors to American Lincoln Corporation, Toledo, Ohio, a corporation of Ohio

Filed June 29, 1964, Ser. No. 80,626

Term of patent 14 years

(Cl. D93—3)

Fig. 1

Fig. 2

Fig. 3

Fig. 6

Fig. 7

FIG. 1 is a view in perspective of a chain saw housing embodying our new design;

FIG. 2 is a left-side elevational view of the housing;

FIG. 3 is a front end elevational view of the housing;

FIG. 4 is a right-side elevational view of the housing;

FIG. 5 is a rear end elevational view of the housing;

FIG. 6 is a top plan view of the housing; and

FIG. 7 is a bottom view of the housing.

The dominant features of the design reside in those portions shown in full lines.

The handle and chain cutting member shown in dotted lines are for illustrative purposes only.

We claim:

The ornamental design for a chain saw housing, substantially as shown and described.
